UNITED STATES PATENT OFFICE.

ROBERT MIEHLE, OF CHICAGO, ILLINOIS.

TRIPPING MECHANISM FOR ROTARY PRINTING-PRESSES.

1,300,289.

Specification of Letters Patent. Patented Apr. 15, 1919.

Application filed April 13, 1917. Serial No. 161,699.

To all whom it may concern:

Be it known that I, ROBERT MIEHLE, citizen of the United States, residing at Chicago, in the county of Cook and State of Illinois, have invented a certain new and useful Improvement in Tripping Mechanism for Rotary Printing-Presses, of which the following is a full, clear, concise, and exact description.

10 My invention relates to tripping mechanisms for printing presses and has particular relation to planographic or offset machines although many of the features thereof are applicable to other types of two impression rotary machines in which during the normal operation thereof the impression elements are not moved out of and restored back into impression relation during each cycle of operation.

20 One of the features of my invention resides in providing controlling devices for presses of the above described character, which are simple in construction and operation and which are adapted to be used in conjunction with two impression rotary machines equipped with tripping mechanism similar to that disclosed in my co-pending application Serial No. 157,979, filed March 28, 1917, for tripping mechanism for printing presses, whereby the impression elements may be tripped in proper sequence with a minimum effort, the advantages of said tripping mechanism obtaining unimpaired.

35 The controlling devices above mentioned are of particular advantage in planographic or offset machines where the tripping and restoration functions of the various impression elements follow each other in close sequence, the operation of the controlling devices allowing sufficient time for all the functions to be performed without necessitating closely adjusted mechanisms which are liable to become deranged.

45 There are numerous specific features embodied in the controlling devices above mentioned which are adapted to operate in harmony with each other to afford a complete controlling device but whose utility is not restricted to such combination.

55 One of these features consists in providing automatic mechanism for controlling the tripping function of the tripping mechanism of the second impression element, which mechanism preferably consists in means operated by the movement of the first

cylinder out of and into operative position for controlling the tripping function of said tripping mechanism and which preferably operates upon a coupler adapted to 60 control the connection between the second impression element and the means for effecting the tripping movement thereof. This feature is supplemented by attendant controlled means for preventing the coupler 65 from operating to effect a connection between the second impression element, and attendant controlled means for effecting connection of the second cylinder with the means for effecting the tripping movements 70 thereof to allow the operator to manually control the tripping movement of the second impression element.

Another of these features resides in providing a control mechanism in addition to 75 the above noted automatic mechanism for controlling the restoring function of the tripping mechanism of the second impression element, which is preferably manually controlled, and which also controls the tripping function of the tripping mechanism of the first impression element, whereby the tripping of the first impression element actuates to cause the second impression element to trip and the controlling mechanism 80 controls the restoring function of the second impression element to allow the same to remain in tripped position for a number of successive cycles without returning to operative position during a portion of each 85 cycle. This control mechanism preferably also controls the restoring function of the tripping mechanism of the first impression element for the same purpose as it controls the restoring function of the tripping mechanism of the second impression element. 90

95 This control mechanism preferably is adapted when in one position to cause the tripping mechanism of the first impression element to trip the first impression element 100 and while it is in this position to prevent the tripping mechanism of the second impression element from functioning to restore, and, if it controls the restoring function of the tripping mechanism of the first 105 impression element, to prevent it from functioning also, and when in another position to prevent the tripping mechanism of the first impression element from functioning to trip and while in this position to prevent 110 the tripping mechanism of the second impression element from functioning, and, if

it controls the restoring function of the tripping mechanism of the first impression element, to prevent it from functioning also.

Another feature resides in providing a moistening mechanism in operative relation with the form cylinder of a rotary planographic press and means whereby the movement of the form cylinder out of printing position operates to move the moistening mechanism partially out of relation with the form cylinder whereby the form cylinder is not moistened too much while running in tripped position.

The invention in the foregoing and other characteristics will be fully described in connection with the accompanying drawings and will be set forth in the claims. In the drawings Figure 1 is a view in side elevation, parts broken away, of a portion of a printing press equipped in accordance with the invention; Fig. 2 is an end view illustrating the arrangement of gearing and cylinders which is preferred; Fig. 3 is a sectional elevation illustrating parts that are disclosed in Figs. 1 and 2 and other parts in addition, the printing and form cylinders being out of printing relation; Fig. 4 is a view similar to Fig. 3 excepting that the printing and form cylinders are in printing relation; Fig. 5 is similar to Fig. 3 excepting that the form cylinder is in printing relation with the printing cylinder; and Fig. 6 is a view in end elevation, with parts in section, of the tripping cam mechanism.

Like parts are indicated by similar characters of reference throughout the different figures.

The mechanism herein illustrated and described is similar in many respects to that shown in my co-pending application, Serial No. 157,979, filed March 28, 1917.

The power for operating the press is derived from a driving shaft 1 upon which there is driving spur pinion 2 upon one side 45 and near one end of the press. This spur pinion meshes with a spur gear 3 fixed upon a stub shaft 4 mounted in the extension 5 bolted to the base of the press frame. The spur gear 3 meshes with a spur gear 6 mounted freely upon a shaft 7 upon which shaft the impression cylinder 8 is fixed. The shaft 7 is journaled in boxes 7¹ that are contained in housings on the side frames of the press. These boxes are normally fixed 55 to give a fixed axis of rotation of the impression cylinder 8 but are vertically adjustable by means of the adjusting screws 7². The gear 9 is fixed upon shaft 7 and meshes with a spur gear 10 which is fixed upon a stub shaft 60 11 journaled in the extension 12 bolted to the base of the press frame. The spur gear 10¹ is co-axial with the spur gear 10 and is also fixed upon the stub shaft 11 by being bolted to the gear 10 with bolts 11¹. The spur gear 65 10¹ is in mesh with a spur gear 10² fixed with

respect to the spur gear 6 by being fixedly mounted upon the hub 6¹ of this latter gear. This hub 6¹ is journaled in a vertically adjustable bracket 12¹ carried upon the extension 12. This gear 10 is a cylinder gear 70 mounted at an end of the printing cylinder 13 but not in fixed relation to the shaft 14 of this cylinder 13. The cylinder shaft 14 is journaled in boxes 15 that are mounted for vertical movement between guides 16 75 upon the press frame 17, the vertically movable boxes permitting movement of the printing cylinder 13 transversely to the axes of the cylinder gear 10 and the axis of the cylinders 8 and 13. The distance between 80 the axes of the gears 9 and 10 is fixed as their shafts 7 and 11 have fixed axes of rotation. As the printing cylinder 13 is adjustable with respect to the axis of its cylinder gear 10 flexible means are employed for connecting said cylinder gear 10 to cylinder 13. This flexible means preferably includes a unison ring or member 18 in the form of a disk which permits the axis of the cylinder gear 10 to remain fixed while the axis of the 85 cylinder may shift, this disk or connecting means 18 being shiftable with respect to said cylinder 13 and said cylinder gear 10. The disk 18 carries two diametrically opposite slotted guideways 19 the slots of which receive the diametrically opposite driving blocks 20 that are carried by the gear 10, these blocks 20 and the slots in the guideways 19 being upon the same diametrical line whereby the disk 18 may shift with respect to the gear 10 along the diametrical line containing the blocks 20. The disk 18 is formed with a groove 21 disposed along the diametrical line that is at right angles to the diametrical line containing the driving 90 blocks 20 and guideways 19. The groove 21 receives a rib 22 carried by the disk 23 and disposed on the diametrical line of this disk. The disk 23 is fixed with respect to the shaft 14 and the cylinder 13. By the means described for connecting the cylinder gear 10 with the printing cylinder 13 the peripheral speed of such cylinder will be maintained the same as the peripheral speed of the cylinder gear 10 (which latter speed is measured at 95 the pitch circle or driving line of the gear teeth) even though said cylinder and cylinder gear are laterally shifted relatively to one another causing relative displacement of their axes. While the printing cylinder 13 is in printing position its axis is preferably coincident with the axis of the cylinder gear 10 but when the cylinder 13 is tripped out of printing position its axis is then non-coincident with the axis of its cylinder gear 10 but this cylinder gear maintains its own fixed axis so that the meshing thereof with the driving gear 9 and the driving thereof is not disturbed. The spur gear 9 meshes with spur gear 24 fixed upon shaft 25 journaled 100

105

110

115

120

125

130

in the side frame 17. The sheet transfer cylinder 26 is fixed upon the shaft 25 and is provided with bearers 26¹. The driven gear 9 thus drives the spur gear 24 to rotate the sheet transfer cylinder 26 at the peripheral speed of the impression cylinder 8. In the press illustrated the cylinders 8 and 26 are each plural revolution cylinders and the cylinder 13 is a single revolution cylinder, each 10 of the cylinders 8 and 26 rotating two revolutions to each revolution of the cylinder 13.

The tripping mechanism employed may be of the general nature illustrated in my Patent No. 550,992, dated December 10, 1895, 15 with necessary changes. The foot key 40 is normally held up by a spring 41 and is connected by a bell crank 42 with a connecting link 43 that is connected with a rocker arm 44 that in turn is fixed upon a rod 45 and 20 on which rod there is fixed a cam arm 46 carrying a trip cam portion 47. Whenever the foot key is depressed the rod 45 of the tripping mechanism is turned to turn the cam arm 46 to move the upper end of the cam arm downwardly and with it the cam 25 47 to allow the hook 48 to come into engagement with the tooth 49. The part 50 of hook 48, the swinging part 51 of the arm 52 and the part 53 of tooth 49 constitute elements of a coupler that connects the printing cylinder 13 with its tripping cam 54. The tripping cam 54 is rotated by a gear 55 upon which the cam is fixedly located, the gear 55 in turn being rotated by the pinion 30 56 which turns upon the stud 57 which is fixed to the frame of the press, the pinion 56 meshing with pinion 57¹ which is in fixed connection with the spur gear 58 (gears 56 and 58 turning on stud 58¹) that is in mesh 35 with the pinion 59 carried upon the outer end of the shaft 1 opposite to that which carries the pinion 2, and which pinion 2 meshes with the gear wheel 3, the shaft 1 passing through the machine from side to 40 side. The cam groove 60 in cam 54 engages a cam roller 61 upon the arm 52 loose on shaft 62 that passes from side to side of the machine and to which shaft the tooth 49 and the stop finger 49¹ are fixed. The roller 45 61 is mounted upon the stud 63 upon the inner end of which the hook 48 is mounted to swing. The shaft 62 carries two eccentrics 64 upon each of which the sliding box member 65 rests, each sliding box member supporting a U-shaped extension 66 of a printing cylinder shaft box 15, there being thus one eccentric 64 in supporting relation to each printing cylinder box 15. Each shaft box 15 is formed in two sections that meet 50 along the horizontal diameter of the shaft 14, these two sections being held in assembly with each other by bolts 66¹. A stationary spring supporting ledge 66² is carried by the press frame, there being one such ledge 55 upon each side of the press. This stationary

ledge 66² passes between the sides of the respective vertically movable extension 66 and supports the springs 66³. These springs abut the respective shaft boxes 15 and support a large part of the weight of the cylinder 13, there being sufficient weight unsupported by these springs to cause the cylinder to descend when the eccentrics 64 are turned to lower positions. The arc *a b* of the cam groove 60 (Fig. 5) is concentric with respect 70 to the shaft 67 of the cam. The cam roller 61 is not bodily moved while engaging this part of the cam groove *a b* whereby the arm 52 is then at rest. The hook 48 carries a cam roller 68 that may bear upon the operating tripping cam portion 47 of the arm 46. The arm 52 carries a stop pin 69 and hook 48 has a lug 70, the elements 69 and 70 preventing the hook 48 from separating any farther from the tooth 48 than illustrated. 85

Each pair of eccentrics 64 upon the same shaft 62 has the position illustrated in Fig. 4 when the printing cylinder 13 is in its normal operating position, the centers of these eccentrics being normally positioned slightly 90 to the left of the vertical line passing through the centers of the shaft 62 and the shaft of the printing cylinder and being between this line and the stationary stop pins 71. As teeth 49 and 49¹ are in fixed relation to the eccentrics 64 the stop pin 71 holds the shaft 62 from counter clockwise rotation to hold the printing cylinder 13 in working position. When the shaft 62 is turned clockwise the eccentrics 64, being 95 fixed upon the shaft, are also turned clockwise so that the printing cylinder is lowered to non-printing position (Fig. 3). This rotation of the shaft 62 and the eccentrics 64 cannot occur until after the part 50 of hook 100 48 is brought into position to enable it to be engaged with the lower side of the tooth 49, following the depression of the foot key (at a time when the cylinder 13 is in an impression position) by the press attendant to 105 lower the arm 46 and the cam part 47 thereon to permit the hook 48 to swing downwardly into the hook engaging position. Operative engagement of the part 50 of the hook 48 with the tooth 49 to effect the tripping movement can only occur while the arcal portion *a b* of the cam groove 60 is passing by the cam roller 61 which is when the line *b*¹ (shown on the cylinder 13, Fig. 5) has passed from the line *a*¹ to the position of the line *b*¹. This tripping may be effected at a time when the cylinder 13 is in a printing position and only during the time the leading edge of the printing form 13¹ travels through the arc *a*² *b*² and during the 115 time the cam roller 61 is passing over the cam portion of the cam groove 60 between the side *a* of the arc *a b* and the shaft 72. The part 50 of the hook 48 (assuming that the attendant has pressed down the key 40 120

to drop the arm 46 to permit the hook 48 to engage the tooth 49) pulls the tooth 49 in a clockwise direction (while the leading end of the form 13¹ is passing between the lines 5 $a^2 b^2$ to permit the printing cylinder 13 to be lowered by its own weight (Fig. 5). When the roller 61 is in the portion of the cam groove 60 between the shaft 72 and the side b of the arc $a b$ (while the leading end of 10 the form 13¹ is passing between the lines $a^4 b^4$), the motion of the arm 52 is reversed, providing the foot key 40 had been previously released, whereupon the swinging extension 51 of the arm 52 pushes upon the 15 lug 53 carried by the tooth 49 to turn this tooth and the eccentrics 64 fixed with respect thereto counter-clockwise back to the normal position, whereby the restoring movement of the cylinder 13 is effected. In coming back to 20 this position the eccentrics 64 raise the printing cylinder to working position. It is to be understood that the roller 68 (upon hook 48) supports the hook while this roller 68 rides over the tripping cam portion 47 when 25 the arm 46 that carries this cam 47 is in its normal raised position and while the printing cylinder is in its normal operating position. The cam arm 46 may be lowered at any time but should this arm be lowered 30 while the roller 61 is not in the arcal portion $a b$ of the cam slot 60 the swinging end of the hook will ride upon the crown of the tooth 49 until the roller 61 is received in the arcal portion $a b$ of said cam groove 60. 35 The cylinder 13 is maintained in its tripped position, while the cylinder 13 is being tripped during a number of successive cycles, by the same foot key 40 that causes the cylinder 13 to be tripped. In order that 40 the key 40 may serve this purpose it is in operating connection with a cam lever 40² that is pivotally mounted upon the frame of the machine, the connection of the foot key with the cam lever 40² including a link 40³ 45 pivotally connected at one end with the lever 40² and at its other end with the arm 42. When the foot key 40 is depressed the lower end of the cam lever 40² is raised to be in the path of movement of and to engage the roller 40⁵ carried by the rocking dog 51 pivoted at 51¹ on the rear side of the arm 52, whereby this rocking dog is raised and relieved of its function of coupling the tripping mechanism of cylinder 50 55 13 with such cylinder to prevent this tripping mechanism from raising the cylinder 13 to printing position. In performing this function the dog 51 normally engages the part 53 of the tooth 49 and as the dog 51 is 60 pivoted at 51¹ to the arm 52 the arm 52 is, through the intermediation of the dog, engaged with the part 53 of the tooth 49. This dog thus, in its normal position, serves as a 65 coupler for connecting the tripping mechanism of cylinder 13 with the cylinder to en-

able such tripping mechanism to restore the cylinder 13 to printing position. When the lower end of the lever 40² is thus raised it lifts the dog 51 out of the path of engagement of the portion 53 of the tooth 49, and 70 permits the dog to ride over such tooth portion when the dog is swung by its operating cam 54. Thus the cylinder 13 is maintained in its lowered position as long as the foot key 40 is depressed and only when the foot 75 key is depressed long enough for this purpose and if it is desired to repeatedly trip the cylinder 13 the foot key may be maintained in a depressed position by turning the eccentric wheel 41 to engage the depressd 80 key 40 whereby the cam 40² and parts connected therewith are maintained in the operating position shown by Fig. 3 to keep the dog 51 from engaging the tooth portion 53. Thus, a controlling or positioning mechanism, comprising the foot key 40 and its associated parts, is provided for the press actuated mechanism for effecting the tripping and restoring movements of the cylinder 13, which, when properly positioned, allows the 85 mechanism to function to effect the tripping movement of the cylinder and while in this position prevents the mechanism from functioning to effect the restoring movement of the cylinder. 90 95

The sheets to be printed upon are fed to the impression cylinder 8 (Fig. 4) from the feed board or other feed structure 73 which is mainly located in the quadrant containing the impression cylinder. The grippers 100 74 upon the impression cylinder 8 take the sheet, numbered 75, from the feed board carrying it through the line 76 joining the centers of the shafts 7 and 25 to the line 77 joining the centers of shafts 7 and 14, whereupon the first printing operation is initiated, the form 13¹ upon the printing cylinder 13 then having printing relation with the sheet 75 upon the impression cylinder 8. A sheet 78 (Fig. 4) upon the sheet transfer cylinder 110 24 is shown preceding the sheet 75, sheet 78 having been held by grippers 79 which held the sheet during more than one revolution of the sheet transfer cylinder 26 after the grippers 79 receive the sheet from grippers 74 115 preparatory to being transferred to the sheet delivery tapes 80. The first printing operation upon the sheet 75 continues during the first revolution of the impression cylinder 8 and a part of the second revolution thereof 120 (beginning with the time the impression cylinder 8 receives the sheet) until the form 13¹ upon the printing cylinder completes its printing upon the sheet 75. During the second revolution of the impression cylinder 8 125 the grippers 79 upon the sheet transfer cylinder 26 take the sheet 75 being printed upon by the form 13¹, the grippers 74 releasing the sheet and the grippers 79 taking the sheet when these grippers of cylinders 130

8 and 26 are adjacent the line 76 during the second revolution of the impression cylinder 8. The transfer of sheet 75 from cylinder 8 to the sheet transfer cylinder 26 (whose center is in the same quadrant with cylinder 8) will not occur until these cylinders have each made nearly one revolution from the position shown in Fig. 4 and at the time grippers 74 again reach line 76.

10 In the embodiment of the invention illustrated the printing element 13¹ is adapted to receive offset printing, being, as illustrated, a rubber blanket that is disposed over the impression portion of the printing cylinder. The printing cylinder 13 thus constitutes a transfer impression cylinder not only forming one member of a printing couple that includes the impression cylinder 8 but also one member of another printing couple which includes a printing cylinder 82. This printing cylinder supports a printing form 83 which may be a type letter or other relief form, or a planographic form. When the form 83 is a relief form it may be either unyielding or resilient, but when resilient the form 13¹ may be unyielding. The form 83 is inked by suitable inking mechanism as hereinafter to be described. The unyielding form 83 prints upon the resilient form 13¹ and this resilient form 13¹ co-operates with the impression cylinder 8 to print upon a sheet whose progress through the press has been described. The printing or form cylinder 82 has a cylinder gear 84 connected therewith and which is in mesh with the cylinder gear 10 connected with the transfer impression cylinder 13. The cylinder gear 84 is desirably connected with the cylinder 82 by a flexible connection. The flexible connection illustrated includes a member 85 in the form of a disk which permits the axis of the cylinder gear 84 to remain fixed while the axis of the cylinder may shift, this disk or connecting means 85 being shiftable with respect to said cylinder 82 and said cylinder gear 84. The disk 85 carries two diametrically opposite slotted guideways 86, the slots of which receive diametrically opposite driving blocks 87 that are carried by the gear 84, these blocks 87 and the slots in the guideways 86 being upon the same diametrical line whereby the disk 85 may shift with respect to the gear 84 along the diametrical line containing the blocks 87. The disk 85 is formed with a groove 88 disposed along the diametrical line that is at right angles to the diametrical line containing the driving blocks 87 and guideways 86. The groove 88 receives a rib 89 carried by the disk 90 and disposed on a diametrical line of this disk. The disk 90 is fixed with respect to the shaft 91 and the cylinder 82. The gear 84 thus may have a fixed axis while the cylinder 82 may be shifted or adjusted into and out of printing

relation with the transfer impression cylinder 13 transversely of the axis of its cylinder gear. In confining the gear 84 to a fixed axis of rotation in order that it may be employed to drive the form inking rollers 92, 93 and provide the flexible connection between the gear 84 and the form cylinder 82 to permit this form cylinder to be moved with respect to the axis of said gear 84 without disturbing the relation between the gear 84 and the gearing that drives the inking mechanism and also without disturbing the relation between the gear 84 and the gear 10. The form inking rollers 92, 93 are arranged, in the embodiment of the invention illustrated, in pairs. The rollers 92 of one pair are driven by the metallic distributing roller 94 and the rollers 93 are driven by the metallic distributing roller 95. The rollers 94 and 95 are respectively driven by pinions 96, 97 that mesh with the pinions 98, 99 upon the rollers 94 and 95. The pinions 96 and 96² are fixed upon shaft 96¹ and the pinions 97 and 97² are fixed upon shaft 97¹, the shafts 96¹ and 97¹ being journaled in the press frame. An intermediate pinion 100 is mounted for rotation on the press frame and meshes with pinions 96² and 97² and with gear 101 also mounted for rotation on the press frame. The gear 101 is in mesh with the gear 84, the axes of these two gears remaining in fixed relation with each other and with the axis of the gear 10 even though the cylinders 13 and 82 are shifted to shift their axes transversely of the axes of their cylinder gears 10 and 84. By the means described for connecting the cylinder gear 84 with the printing or form cylinder 82, the peripheral speed of such cylinder will be maintained the same as the peripheral speed of the inking rollers 92, 93, the gearing interposed between the gear 84 and the form inking rollers 92 and 93 being designed to have the peripheral speed of the inking rollers the same as that of the cylinder 82. While the printing cylinder 82 is in printing position its axis is preferably coincident with the axis of the cylinder gear 84 but when the cylinder 82 is moved out of printing position its axis is then non-coincident with the axis of this cylinder gear 84. When the cylinder 82 is moved out of printing position it is also moved substantially out of inking relation with the form inking rollers 92, 93 but these form inking rollers continue to turn at substantially the peripheral speed of the cylinder 82 so that when the cylinder 82 is restored to printing relation with the cylinder 13 and inking relation with the inking rollers 92, 93 there will be substantially no wiping action of these inking rollers upon form 83 or substantially no wiping action of the form 83 upon such inking rollers so that neither the form nor the inking rollers will be injured and the inking of the form 130

will not be marred. The peripheral speed of the form 13¹ and the form 83 are also the same in all positions of the cylinders 13 and 82 due to the fact that their cylinder gears have their axes maintained in fixed relation and position (due to the flexible connections between these cylinders and their cylinder gears) whereby neither form 13¹ nor 83 will have wiping action upon the other to mar or injure either while in printing relation whether or not the axes of such cylinders are coincident with the axes of their gears. In the press illustrated the cylinder 82 is a plural revolution cylinder, rotating twice for one revolution of the cylinder 13. In one revolution of the cylinder 82 it prints upon the form 13¹ and in the second revolution of this cylinder 82 it rolls over the blank or non-printing side 13² of cylinder 13.

If the form 83 is a planographic form it is provided with moistening mechanism shown upon the upper side of the cylinder 82. This moistening mechanism includes a water containing trough or reservoir 102 in which a suitable supply roller 103 turns. This moistening mechanism includes the usual feed roller 104 mounted upon arms 105 to which oscillatory movement is imparted whereby the roller 104 may be intermittently and alternately applied to the rollers 103 and 106. The roller 106 transfers the water to the main moistening rollers 107 that bear upon the form 83 when its cylinder 82 is in printing position. A train of gears, not shown, drives these rollers from the press mechanism. The carrying frames 102¹ of the moistening mechanism are rigidly connected by a rod 102² that is pivoted upon the side frames of the press. The lower end of one of the rigidly connected frames 102¹ rests against the eccentric stop 102³. The attendant may lift the moistening mechanism from the form 83 at any time by turning the high side of the eccentric 102³ into lifting engagement with the frame 102¹ (Fig. 4), the eccentric 102³ being provided with a handle 102⁷ for this purpose. The handle 102⁷ normally engages the stop 102³ to keep the low side of the eccentric 102³ opposite the frame 102¹. The handle 102⁷ is limited in its moistener raising movement by the stop 102³. When the cylinder 82 is raised to non-printing position the cylinder 82 will engage the bearing roller 107¹ to automatically swing the frames 102¹ toward a disengaged position to clear the lower moistening roller 107 only from the form 83 whereby the amount of moisture supplied to the cylinder 82 when in a tripped or non-printing position is materially reduced while at the same time this cylinder receives sufficient moisture from the upper roller 107 to prevent it from becoming too dry when the cylinder is repeatedly tripped in succession (Fig. 7).

The cylinder 82 is adapted to be brought into and out of printing relation with the cylinder 13 along the line which is inclined with respect to the line joining the centers of the shafts of these cylinders while the cylinder 13 is moved into and out of printing relation with the cylinder 8 along the line that is perpendicular to the aforesaid line and which line of movement of the cylinder 13 is the vertical diametrical line 81 that defines the quadrant in which the cylinders 8 and 26 are contained, in the preferred form of the invention, and the quadrant in which the centers of the cylinders 8 and 82 are substantially included. The tripping mechanism which is employed for tripping the printing cylinder 82 to non-printing position is generally similar to the tripping mechanism pertaining to the cylinder 13 and like parts of the two tripping mechanisms are given similar characters of reference. The cylinder 82, however, is moved upwardly when it is tripped out of printing relation with cylinder 13 whereas cylinder 13 is moved downwardly when this cylinder is tripped out of printing relation with cylinder 6. Springs 82¹ serve to elevate the cylinder 82 to non-printing position and hold it in that position when tripped, the position to which the springs 82¹ may elevate the cylinder 82 being defined and limited by the arm 49² (Fig. 1) fixed to the shaft 62 with respect to the left hand tooth 49 and the pin 71¹ carried by the frame of the press and engaged by the arm 49² when the cylinder 82 is in its uppermost position. The left hand eccentrics 64 operate the sliding boxes 64¹ in the openings of the extension 64² of the cylinder shaft boxes 64³ of the cylinder 82. These boxes 64¹ are permitted movement laterally of the line of shifting movement of the cylinder 82 in order that the eccentrics may operate them. These eccentrics 64 serve to lower the cylinder 82 to printing position, against the force of the springs 82¹, the eccentrics being moved to dead center with respect to the center of the cylinder 82 to lock the cylinder 82 in printing position. The tripping mechanism of cylinder 82 differs in some respects from the tripping mechanism of the cylinder 13 and these differences will be described in connection with the mechanism which is employed for controlling this tripping mechanism to occasion tripping movement of its cylinder 82. The tripping function of the tripping mechanism of the cylinder 82 is governed by the mechanism that operates the cylinder 13. When the cylinder 13 is in printing relation with the impression cylinder 8 (Fig. 4) the cam 108 upon the shaft 14 is in controlling relation to the tripping mechanism of cylinder 82. When the cylinder 13 is out of printing relation with the impression cylinder 8 (Fig. 5) the cam 108 has no controlling action over

the tripping mechanism of cylinder 82. Cam 108 has a raised portion 109 that engages cam roller 110 once in each revolution of the shaft 14, parts of the cam, other than 5 the raised portion 109 thereof, remaining out of operating engagement with said cam roller. The cam portion 109 raises the roller 110 to turn the lever 111 that carries said roller in a clockwise direction, and is 10 so timed relatively to the trip cam 54¹ of the cylinder 82 that it passes the roller 110 while the roller 61 of the cam arm 52 of the tripping mechanism of cylinder 82 is passing the portion of the cam groove 60 lying between 15 the arc *a b* thereof. The function of the cam 10 is fully explained in my application Serial No. 153,469, filed March 8, 1917, in which the same is claimed as an element in a combination similar to the above, and needs no 20 further explanation here. The lower end of the lever 111 carries a pin 112 which is cut by the plane of movement of the finger 46¹ carried by the cam arm 46. When the cam roller 110 is raised the pin 112 engages the 25 finger 46¹ and moves the cam arm 46 counter-clockwise to move the cam portion 47 into the arcal path of the roller 68 that is carried by the hook 48 to prevent this hook from dropping into engagement with the tooth 49 30 to prevent the effecting the tripping movement of mechanism of cylinder 82 from tripping its cylinder. When the cam roller 110 is out of engagement with the effective portion 109 of the cam 108, the pin 112 is drawn 35 to the right whereupon the cam arm 46 moves in a clockwise direction due to its own weight. When the arm 46 is moved in a clockwise direction the cam portion 47 is moved in a similar direction out of the path 40 of the roller 68 so that the part 50 of the hook 48 may be permitted to engage the tooth 49 to trip the cylinder 82 out of printing relation with the cylinder 13 when the cylinder 13 is tripped out of printing relation 45 with the cylinder 82. In Fig. 5 the engagement of the hook 48 with the tooth 49 is shown due to the movement of the pin 112 to the right, this pin being positioned to the right when the cylinder 13 is depressed to 50 a non-printing position, as illustrated in Fig. 2, and in which position the cam 108 is not effective to control the lever 111 since the hook 48 should be engageable with the tooth 49 when the cylinder 13 is tripped to 55 a non-printing position in which case the cylinder 82 is tripped to a non-printing position, as shown in Fig. 3. The hook 48 and the tooth 49 of the mechanism pertaining to cylinder 82 constitutes members of a coupler 60 for associating the tripping mechanism of this cylinder with such cylinder acting similarly to the hook 48 and tooth 49 of the tripping mechanism pertaining to cylinder 13, but being controlled by a member of a 65 printing couple rather than by a foot key and acting automatically. All that which has been said about the arc *a b* may be said about the tripping mechanism of cylinder 82. The tripping action of this cylinder 82 occurs when the leading end of the form 70 on cylinder 82 passes from the line *a⁵* to the line *b⁵*. In the arrangement of the tripping mechanism of the cylinder 82 the cam gear 55 thereof meshes with the broad faced pinion 55², this pinion in turn meshing with 75 cam gear 55² of cam 54¹ of the tripping mechanism of cylinder 82, said gears 55, 55² being in different planes of rotation. 80 While the cylinder 13 is tripped the cylinder 82 should remain in its tripped position as long as the cylinder 13 is continuously and successively tripped, it being desired to maintain the cylinder 82 in tripped position while the cylinder 13 is in a tripped position to keep the cylinder 82 substantially out of inking relation with its inking mechanism and out of moistening relation with one of its moistening rollers while cylinder 13 is tripped. The cylinder 82 is maintained in its tripped position, while the cylinder 13 is being repeatedly tripped, by the 85 same foot key 40 that causes the cylinder 13 to be tripped. In order that the key 40 may serve this purpose it is in operating connection with a cam lever 113 that is pivotally 90 mounted upon the frame of the machine, the connection of the foot key with the cam lever 113 including a link 114 pivotally connected at one end with the lever 113 and at its other end with the arm 115 that is in fixed relation with the arm 44 and the rod 45. When the foot key 40 is depressed the lower end of cam lever 113 is raised to be in the path of movement of and to engage the roller 116 carried by the rocking dog 117 pivoted at 95 118 on the rear side of the arm 52, whereby this rocking dog is relieved of its function of coupling the tripping mechanism of cylinder 82 with such cylinder to prevent this 100 tripping mechanism from lowering or restoring the cylinder 82 to printing position. In performing this function the dog 117 normally engages the part 53 of the tooth 49 and as the dog 117 is pivoted at 118 to the arm 52 the arm 52 is, through the inter-mediation of the dog, engaged with the part 105 53 of the tooth 49 with the results which will be understood from the description which has been given of the tripping mechanism of cylinder 13 since the dog 117 corresponds 110 generally to the part 51 of the arm 50 of cylinder 13. This dog thus, in its normal position, serves as a coupler for connecting the tripping mechanism of cylinder 82 with the cylinder to enable such tripping mechanism to lower the cylinder 82 to printing position. When the lower end of the lever 113 is thus raised it lifts the dog 117 out of the 115 path of engagement of the portion 53 of the tooth 49, and permits the dog to ride over 120 125 130

such tooth portion when the dog is swung by its operating cam 54. Thus the cylinder 82 is maintained in its raised or tripped position by the spring 82¹ as long as the foot key 40 is depressed and only when the foot key is depressed long enough for this purpose and if it is desired to repeatedly trip the cylinder 82 the foot key may be maintained in a depressed position by turning the eccentric wheel 41¹ to engage the depressed key 40 whereby the cam 113 and parts connected therewith are maintained in the operating position shown in Fig. 3 to keep the dog 117 from engaging the tooth portion 53.

15 It will be noted at this point that, when the key 40 of the controlling mechanism is depressed, the tripping mechanism of the cylinder 13 is allowed to function to effect the tripping movement of that cylinder and is prevented from functioning to effect the restoring movement of that cylinder and, while in this position, the tripping mechanism of the cylinder 82 is prevented from functioning to effect the restoring movement of this cylinder.

If it is desired to enable the attendant to move the lever 111 to produce the same action that the cam 108 produces this lever may be equipped with a handle 111¹ for this purpose. The influence of the cam 108 upon the lever 111 may be removed by providing a shiftable mounting fulcrum for the lever. To this end the trunnion pin 111² of the lever 111 is eccentrically mounted upon the 30 stub shaft 111³ that is journaled in the frame of the press. This stub shaft 111³ is provided with a handle 111⁴ which normally rests against the stop 111⁵. When the handle 111⁴ is moved around against the stop 40 111⁶ the fulcrum 111² of the lever 111 is elevated to place this lever in the position illustrated in Fig. 4, and in which position the roller 110 is without the operating range of the cam 108 and the pin 112 is maintained 45 out of engagement with the finger 46¹.

While I have herein shown and particularly described the preferred embodiment of my invention I do not wish to be limited to the precise details of construction shown as 50 changes may readily be made without departing from the spirit of my invention, but having thus described my invention I claim as new and desire to secure by Letters Patent the following:—

55 1. A printing press including a cylinder; means for moving the cylinder into and out of operative position; a second cylinder; means for effecting tripping movement of the second cylinder; a coupler for connecting the second cylinder with its tripping mechanism; and mechanism for operating the coupler to disconnect the second cylinder from its tripping mechanism and operable by the first cylinder when in operating 60 position.

2. A printing press including a cylinder; means for moving the cylinder into and out of operative position; a second cylinder; means for effecting tripping movement of the second cylinder; a coupler for connecting the second cylinder with its tripping mechanism; and mechanism for operating the coupler to disconnect the second cylinder from its tripping mechanism and operable by the first cylinder when in operating 70 position, the first cylinder losing control over the coupler operating mechanism when the first cylinder is out of operating position.

3. A printing press including a cylinder; means for moving the cylinder into and out of operative position; a second cylinder; means for effecting tripping movement of the second cylinder; a coupler for connecting the second cylinder with its tripping mechanism; and positioning means governed by the first cylinder when in operating position for preventing the coupler from connecting the second cylinder with its tripping mechanism.

4. A printing press including a cylinder; means for moving the cylinder into and out of operative position; a second cylinder; means for effecting tripping movement of the second cylinder; a coupler for connecting the second cylinder with its tripping mechanism; and positioning means governed by the first cylinder when in operating position for preventing the coupler from connecting the second cylinder with its tripping mechanism, the first cylinder having its influence upon the positioning means removed when this first cylinder is out of operating position to permit said tripping mechanism to be coupled with the second cylinder.

5. A printing press including a cylinder; means for moving the cylinder into and out of operative position; a second cylinder; means for effecting tripping movement of the second cylinder; a coupler for connecting the second cylinder with its tripping mechanism; positioning means governed by the first cylinder when in operating position for preventing the coupler from connecting the second cylinder with its tripping mechanism, the first cylinder having its influence upon the positioning means removed when this first cylinder is out of operating position to permit said tripping mechanism to be coupled with the second cylinder; and attendant controlled means for preventing the coupler from connecting the second cylinder with its tripping mechanism when the first cylinder is out of operating position.

6. A printing press including a cylinder; means for moving the cylinder into and out of operative position; a second cylinder; means for effecting tripping movement of the second cylinder; a coupler for connecting the second cylinder with its tripping mecha-

nism; positioning means governed by the first cylinder when in operating position for preventing the coupler from connecting the second cylinder with its tripping mechanism, the first cylinder having its influence upon the positioning means removed when this first cylinder is out of operating position to permit said tripping mechanism to be coupled with the second cylinder; and attendant controlled means for effecting connection of the second cylinder with its tripping mechanism while the first cylinder is in operating position.

7. A printing press including a cylinder; means for moving the cylinder into and out of operative position; a second cylinder; means for effecting tripping movement of the second cylinder; a coupler for connecting the second cylinder with its tripping mechanism; positioning means governed by the first cylinder when in operating position for preventing the coupler from connecting the second cylinder with its tripping mechanism, the first cylinder having its influence upon the positioning means removed when this first cylinder is out of operating position to permit said tripping mechanism to be coupled with the second cylinder; attendant controlled means for preventing the coupler from connecting the second cylinder with its tripping mechanism when the first cylinder is out of operating position; and attendant controlled means for effecting connection of the second cylinder with its tripping mechanism while the first cylinder is in operating position.

8. A printing press including a printing cylinder; an impression cylinder in printing relation with the printing cylinder; means for moving the printing cylinder into and out of operative position; a form cylinder in printing relation with the printing cylinder; means for effecting tripping movement of the form cylinder; means for effecting restoring movement of the form cylinder; mechanism controlled by the printing cylinder for directly controlling the tripping mechanism of the form cylinder; and attendant controlled means for controlling the restoring movement of the form cylinder.

9. A printing press including a printing cylinder; an impression cylinder in printing relation with the printing cylinder; means for moving the printing cylinder into and out of operative position; a form cylinder in printing relation with the printing cylinder; means for effecting tripping movement of the form cylinder; means for effecting restoring movement of the form cylinder; mechanism controlled by the printing cylinder for directly controlling the tripping mechanism of the form cylinder; attendant controlled means for controlling the restoring movement of the form cylinder.

cylinder; and attendant controlled means for also controlling the tripping movement of the form cylinder.

10. A printing press including a printing cylinder; an impression cylinder in printing relation with the printing cylinder; means for moving the printing cylinder into and out of operative position; a planographic form cylinder in printing relation with the printing cylinder; means for effecting tripping movement of the form cylinder; means for effecting restoring movement of the form cylinder; mechanism controlled by the printing cylinder for directly controlling the tripping mechanism of the form cylinder; and attendant controlled means for controlling the restoring movement of the form cylinder.

11. A printing press including a printing cylinder; an impression cylinder in printing relation with the printing cylinder; means for moving the printing cylinder into and out of operative position; a planographic form cylinder in printing relation with the printing cylinder; means for effecting tripping movement of the form cylinder; means for effecting restoring movement of the form cylinder; mechanism controlled by the printing cylinder for directly controlling the tripping mechanism of the form cylinder; attendant controlled means for controlling the restoring movement of the form cylinder; and attendant controlled means for also controlling the tripping movement of the form cylinder.

12. A rotary planographic printing press including a printing couple containing an impression cylinder and a transfer impression cylinder; a form cylinder in printing relation to the transfer impression cylinder; moistening mechanism for the form cylinder; tripping mechanism for breaking the printing relation between cylinders of the aforesaid printing couple; tripping mechanism for breaking the printing relation between said form cylinder and the transfer impression cylinder; means for moving said moistening mechanism toward a non-moistening position when said last mentioned tripping mechanism is actuated to break the printing relation between said form and printing cylinder; a coupler for operatively associating the latter tripping mechanism with its cylinder; and means governed by the mechanism of said printing couple when the members of said couple are in printing relation, for preventing said coupler and its associated tripping mechanism from functioning.

13. A rotary planographic printing press including a printing couple containing an impression cylinder and a transfer impression cylinder; a form cylinder in printing relation to the transfer impression cylinder; moistening mechanism for the form cylinder.

der; tripping mechanism for breaking the printing relation between cylinders of the aforesaid printing couple; tripping mechanism for breaking the printing relation between said form cylinder and the transfer impression cylinder; means for moving said moistening mechanism toward a non-moistening position when said last mentioned tripping mechanism is actuated to break the printing relation between said form and printing cylinders; a coupler for operatively associating the latter tripping mechanism with its cylinder; means governed by the mechanism of said printing couple when the members of said couple are in printing relation, for preventing said coupler and its associated tripping mechanism from functioning; and attendant controlled means for causing said form cylinder to be in connection with its tripping mechanism.

14. A rotary printing press including a printing couple containing an impression cylinder and a printing cylinder; a form cylinder in printing relation to the printing cylinder; tripping mechanism for breaking the printing relation between cylinders of the aforesaid printing couple; tripping mechanism for breaking the printing relation between said form cylinder and the printing cylinder; a coupler for operatively associating the latter tripping mechanism with its cylinder; and means governed by the mechanism of said printing couple when the members of said couple are in printing relation for preventing said coupler and its associated tripping mechanism from functioning.

15. A rotary printing press including a printing couple containing an impression cylinder and a printing cylinder; a form cylinder in printing relation to the printing cylinder; tripping mechanism for breaking the printing relation between cylinders of the aforesaid printing couple; tripping mechanism for breaking the printing relation between said form cylinder and the printing cylinder; a coupler for operatively associating the latter tripping mechanism with its cylinder; means governed by the mechanism of said printing couple when the members of said couple are in printing relation, for preventing said coupler and its associated tripping mechanism from functioning; and attendant controlled means for causing said form cylinder to be in connection with its tripping mechanism.

16. A rotary planographic press including a form cylinder; inking mechanism for the form cylinder; moistening mechanism for the form cylinder; tripping mechanism for moving the form cylinder out of inking relation with the inking mechanism; and means whereby the form cylinder will move the moistening mechanism partially out of

relation with the form cylinder when this cylinder is tripped.

17. A rotary planographic press including a form cylinder; inking mechanism for the form cylinder; moistening mechanism for the form cylinder, this moistening mechanism including a plurality of moistening rollers; tripping mechanism for moving the form cylinder out of inking relation with the inking mechanism; and means whereby the form cylinder will move the moistening mechanism partially out of relation with the form cylinder by removing one of said moistening rollers from engagement with the form cylinder when said form cylinder is tripped.

18. A rotary planographic press including a form cylinder; inking mechanism for the form cylinder; moistening mechanism for the form cylinder, this moistening mechanism including a plurality of moistening rollers and a swingingly mounted frame that supports said rollers; tripping mechanism for moving the form cylinder out of inking relation with the inking mechanism, said form cylinder and moistening mechanism being relatively positioned to enable the form cylinder to swing the moistening mechanism to remove one of the moistening rollers from the form cylinder without removing the other when the form cylinder is placed out of inking relation with the inking mechanism.

19. A rotary planographic press including a printing couple that contains a form cylinder; inking mechanism for the form cylinder; moistening mechanism for the form cylinder; tripping mechanism for placing the form cylinder out of printing relation; and means whereby the form cylinder will move the moistening mechanism partially out of relation with the form cylinder when moved to non-printing position.

20. A rotary planographic press including a printing couple that contains a form cylinder; inking mechanism for the form cylinder; moistening mechanism for the form cylinder, this moistening mechanism including a plurality of moistening rollers; tripping mechanism for placing the form cylinder out of printing relation; and means whereby the form cylinder will move the moistening mechanism partially out of relation with the form cylinder when moved to non-printing position by removing one of said moistening rollers from engagement with the form cylinder.

21. A rotary planographic press including a printing couple that contains a form cylinder; inking mechanism for the form cylinder; moistening mechanism for the form cylinder, this moistening mechanism including a plurality of moistening rollers and a swingingly mounted frame that supports

- said rollers; tripping mechanism for placing the form cylinder out of printing relation, said form cylinder and moistening mechanism being relatively positioned to enable 5 the form cylinder to swing the moistening mechanism to remove one of the moistening rollers from the form cylinder without removing the other when the form cylinder is placed out of printing position.
- 10 22. A rotary planographic press including a printing couple that contains a form cylinder; inking mechanism for the form cylinder; moistening mechanism for the form cylinder; tripping mechanism for tripping the form cylinder out of relation with the inking mechanism and out of printing position; and means whereby the form cylinder will move the moistening mechanism partially out of relation with the form cylinder when tripped.
- 15 23. A rotary printing press including two movably mounted cylinders; of a press actuated mechanism for each cylinder having operable connection with its respective cylinder and being adapted to trip the same out of printing position and to restore the same into printing position; a controlling mechanism having operable connection with one of said mechanisms and adapted to control the same and having operable connection with the other mechanism and adapted to control the same relatively to its restoring function; and automatic mechanism having operable connection with said other press actuated mechanism and adapted to control the same relatively to its tripping function.
- 20 24. A rotary printing press including two movably mounted cylinders; of a press actuated mechanism for each cylinder having operable connection with its respective cylinder and being adapted to trip the same out of printing position and to restore the same into printing position; a controlling mechanism having operable connection with one of said mechanisms and adapted to control the same relatively to its tripping function and having operable connection with the other mechanism and adapted to control the same relatively to its restoring function; said controlling mechanism being adapted to be positioned to allow said one mechanism to function to trip and while in this position to prevent said other mechanism to function to restore; and automatic mechanism having operable connection with said other press actuated mechanism and adapted to control the same relatively to its tripping function.
- 25 25. A rotary printing press including two movably mounted cylinders; of a press actuated mechanism for each cylinder having operable connection with its respective cylinder and being adapted to trip the same out of printing position and to restore the same into printing position; a controlling mechanism having operable connection with one of said mechanisms and adapted to control the same relatively to its tripping function and having operable connection with the other mechanism and adapted to control the same relatively to its restoring function; and automatic mechanism having operable connection with said other press actuated mechanism and adapted to control the same relatively to its tripping function.
- 30 26. A rotary printing press including two movably mounted cylinders; of a press actuated mechanism for each cylinder having operable connection with its respective cylinder and being adapted to trip the same out of printing position and to restore the same into printing position; a controlling mechanism having operable connection with one of said mechanisms and adapted to control the same relatively to its restoring function, said controlling mechanism being adapted to be positioned to allow said one mechanism to function to trip and while in this position to prevent said other mechanism to function to restore; and automatic mechanism having operable connection with said other press actuated mechanism and adapted to control the same relatively to its tripping function.
- 35 27. A rotary printing press including two movably mounted cylinders; of a press actuated mechanism for each cylinder having operable connection with its respective cylinder and being adapted to trip the same out of printing position and to restore the same into printing position; a controlling mechanism having operable connection with one of said mechanisms and adapted to control the same relatively to its tripping function and having operable connection with the other mechanism and adapted to control the same relatively to its restoring function, said controlling mechanism being adapted to be positioned to allow said one mechanism to function to trip and while in this position to prevent said other mechanism to function to restore.
- 40 28. A rotary printing press including two movably mounted cylinders; of a press actuated mechanism for each cylinder having operable connection with its respective cylinder and being adapted to trip the same out of printing position and to restore the same into printing position; a controlling mechanism having operable connection with one of said mechanisms and adapted to control the same relatively to its tripping and restoring functions and having operable connection with the other mechanism and adapted to control the same relatively to its restoring function, said controlling mechanism being adapted to be positioned to allow said one mechanism to function to trip and while in this position to prevent both of said
- 45 50 55 60 65 70 75 80 85 90 95 100 105 110 115 120 125

press actuated mechanisms from functioning to restore; and automatic mechanism having operable connection with said other press actuated mechanism and adapted to 5 control the same relatively to its tripping function.

29. A rotary printing press including a movably mounted cylinder; of a second movably mounted cylinder; of a press actuated mechanism for each cylinder having operable connection with its respective cylinder and being adapted to trip the same out of printing position and to restore the same into printing position; a controlling mechanism having operable connection with the press actuated mechanism of the first cylinder and adapted to control the same and having operable connection with the press actuated mechanism of the first cylinder and adapted to control the same relatively to its restoring function; and mechanism operated by the movement of said first cylinder out of and into printing position and having operable connection with the press actuated mechanism of said second cylinder and adapted to prevent said mechanism from functioning to trip when said first cylinder is in printing position.

30. A rotary printing press including a movably mounted cylinder; of a second movably mounted cylinder; of a press actuated mechanism for each cylinder having operable connection with its respective cylinder and being adapted to trip the same out of printing position and to restore the same into printing position, a controlling mechanism having operable connection with the press actuated mechanism of the first cylinder and adapted to control the same relatively to its tripping function and having operable connection with the press actuated mechanism of said second cylinder and adapted to control the same relatively to its restoring function, and mechanism operated by the movement of said first cylinder out of and into printing position and having operable connection with the press actuated mechanism of said second cylinder and adapted to prevent said mechanism from functioning to trip when said first cylinder is in printing position.

31. A rotary printing press including a movably mounted cylinder; of a second movably mounted cylinder; of a press actuated mechanism for each cylinder having operable connection with its respective cylinder and being adapted to trip the same out of printing position and to restore the same into printing position; a controlling mechanism having operable connection with the press actuated mechanism of the first cylinder and adapted to control the same relatively to its tripping and restoring functions, and having operable connection with the press actuated mechanism of said sec-

ond cylinder and adapted to control the same relatively to its restoring function; and mechanism operated by the movement of said first cylinder out of and into printing position and having operable connection 70 with the press actuated mechanism of said second cylinder and adapted to prevent said mechanism from functioning to trip when said first cylinder is in printing position.

32. A rotary printing press including a 75 movably mounted cylinder; of a second movably mounted cylinder; of a press actuated mechanism for each cylinder having operable connection with its respective cylinder and being adapted to trip the same out of 80 printing position and to restore the same into printing position; a controlling mechanism having operable connection with the press actuated mechanism of the first cylinder and adapted to control the same and having operable connection with the press actuated mechanism of said second cylinder and adapted to control the same relatively to its 85 restoring function, said controlling mechanism being adapted to be positioned to allow the press actuated mechanism of said first cylinder to function to trip and, while in this position, to allow said other mechanism to function to restore; and mechanism operated by the movement of said first cylinder 90 out of and into printing position and having operable connection with the press actuated mechanism of said second cylinder and adapted to prevent said mechanism from functioning to trip when said first cylinder 100 is in printing position.

33. A rotary printing press including a movably mounted cylinder; of a second movably mounted cylinder; of a press actuated 105 mechanism for each cylinder having operable connection with its respective cylinder and being adapted to trip the same out of printing position and to restore the same into printing position; a controlling mechanism having operable connection with the press actuated mechanism of the first cylinder and adapted to control the same relatively to its 110 tripping function and having operable connection with the press actuated mechanism of said second cylinder and adapted to control the same relatively to its restoring function, said controlling mechanism being adapted to be positioned to allow the press actuated mechanism of said first cylinder to function to trip and, while in this 115 position, to allow said other mechanism to function to restore; and mechanism operated by the movement of said first cylinder out of and into printing position and having operable connection with the press actuated 120 mechanism of said second cylinder and adapted to prevent said mechanism from functioning to trip when said first cylinder 125 is in printing position.

34. A rotary printing press including a 130

movably mounted cylinder; of a second movably mounted cylinder; of a press actuated mechanism for each cylinder having operable connection with its respective cylinder 5 and being adapted to trip the same out of printing position and to restore the same into printing position; a controlling mechanism having operable connection with the press actuated mechanism of the first cylinder 10 and adapted to control the same relatively to its tripping and restoring functions and having operable connection with the press actuated mechanism of said second cylinder and adapted to control the same relatively to its restoring function, said controlling mechanism being adapted to be positioned to allow the press actuated mechanism of said first cylinder to function to trip and, while in this position, to prevent both 15 of said press actuated mechanisms from functioning to restore, and mechanism operated by the movement of said first cylinder out of and into printing position and having operable connection with the press actuated mechanism of said second cylinder and adapted to prevent said mechanism from functioning to trip when said first cylinder 20 is in printing position.

35. A rotary planographic printing press 30 including a printing couple containing an impression cylinder and a transfer impression cylinder; a form cylinder in printing relation to the transfer impression cylinder; moistening mechanism for the form cylinder; tripping mechanism for breaking the printing relation between the cylinders of the aforesaid printing couple; tripping mechanism for breaking the printing relation between said form cylinder and the 35 transfer impression cylinder; automatic means operating upon said moistening mechanism to move the same toward a disengaged position relative to moistening said form cylinder when said form cylinder is moved to tripped position; a coupler for 40 operatively associating the latter tripping mechanism with its cylinder; and means governed by the mechanism of said printing couple, when the members of said couple are 45 in printing relation, for preventing said coupler and its associated tripping mechanism from functioning.

36. A rotary offset printing press including a printing couple containing an impression cylinder and a transfer impression cylinder; a form cylinder in printing relation to the transfer impression cylinder; tripping mechanism for breaking the printing relation between the cylinders of the afore- 55 said printing couple; tripping mechanism for breaking the printing relation between said form cylinder and the transfer impression cylinder; inking mechanism for said form cylinder and disposed to be substantially out of inking relation with said form 60 cylinder.

cylinder when it is in the position into which it is moved when tripped; a coupler for operatively associating the latter tripping mechanism with its cylinder; and means governed by the mechanism of said printing couple, when the members of said couple are in printing relation, for preventing said coupler and its associated tripping mechanism from functioning.

37. A rotary planographic printing press 75 including a printing couple containing an impression cylinder and a transfer impression cylinder; a form cylinder in printing relation to the transfer impression cylinder; moistening mechanism for the form cylinder; tripping mechanism for breaking the printing relation between the cylinders of the aforesaid printing couple; tripping mechanism for breaking the printing relation between said form cylinder and the 80 transfer impression cylinder; inking mechanism for said form cylinder and disposed to be substantially out of inking relation with said form cylinder when it is in the position into which it is moved when tripped; automatic means operating upon said moistening mechanism to move the same toward a disengaged position relative to moistening said form cylinder when said form cylinder is moved to tripped position; a coupler for 85 operatively associating the latter tripping mechanism with its cylinder; and means governed by the mechanism of said printing couple, when the members of said couple are 90 in printing relation, for preventing said coupler and its associated tripping mechanism from functioning.

38. A rotary planographic printing press including a printing couple containing an impression cylinder and a transfer impression 105 cylinder; a form cylinder in printing relation to the transfer impression cylinder; moistening mechanism for the form cylinder; tripping mechanism for breaking the printing relation between the cylinders of the aforesaid printing couple; tripping mechanism for breaking the printing relation between said form cylinder and the transfer impression cylinder; automatic means operating upon said moistening mechanism to move the same toward a disengaged position relative to moistening said form cylinder when said form cylinder is moved to tripped position; a coupler for 110 operatively associating the latter tripping mechanism with its cylinder; means governed by the mechanism of said printing couple, when the members of said couple are in printing relation, for preventing said coupler and its associated tripping mechanism from functioning; and attendant controlled means for causing said form cylinder to be in connection with its tripping mechanism.

39. A rotary offset printing press including a printing couple containing an impres- 120

125

- 5 sion cylinder and a transfer impression cylinder; a form cylinder in printing relation to the transfer impression cylinder; tripping mechanism for breaking the printing relation between the cylinders of the afore-
5 said printing couple; tripping mechanism for breaking the printing relation between said form cylinder and the transfer impression cylinder; inking mechanism for said
10 form cylinder and disposed to be substantially out of inking relation with said form cylinder when it is in the position into which it is moved when tripped; a coupler for operatively associating the latter tripping mechanism with its cylinder; means governed by the mechanism of said printing couple, when the members of said couple are in printing relation, for preventing said coupler and its associated tripping mechanism from functioning; and attendant controlled means for causing said form cylinder to be in connection with its tripping mechanism.
- 15 40. A rotary planographic printing press including a printing couple containing an impression cylinder and a transfer impression cylinder; a form cylinder in printing relation to the transfer impression cylinder; moistening mechanism for the form cylinder; tripping mechanism for breaking the printing relation between the cylinders of the aforesaid printing couple; tripping mechanism for breaking the printing relation between said form cylinder and the transfer impression cylinder; inking mechanism for said form cylinder and disposed to be substantially out of inking relation with said form cylinder when it is in the position into which it is moved when tripped; automatic means operating upon said moistening mechanism to move the same toward a disengaged position relative to moistening said form cylinder when said form cylinder is moved to tripped position; a coupler for operatively associating the latter tripping mechanism with its cylinder; means governed by the mechanism of said printing couple, when the members of said couple are in printing relation for preventing said coupler and its associated tripping mechanism from functioning; and attendant controlled means for causing said form cylinder to be in connection with its tripping mechanism.
